C. S. BUSHNELL

TRAIN CONTROL COMMUNICATING ELEMENT

Filed Feb. 25, 1924

FIG. 1.

FIG. 2.

FIG. 3.

FIG. 4.

INVENTOR
Charles S. Bushnell,
BY Neil H. Weston,
his ATTORNEY

UNITED STATES PATENT OFFICE.

CHARLES S. BUSHNELL, OF ROCHESTER, NEW YORK, ASSIGNOR TO GENERAL RAILWAY SIGNAL COMPANY, OF ROCHESTER, NEW YORK.

TRAIN-CONTROL COMMUNICATING ELEMENT.

Application filed February 25, 1924. Serial No. 694,993.

To all whom it may concern:

Be it known that I, CHARLES S. BUSHNELL, a citizen of the United States of America, residing at Rochester, in the county of Monroe and State of New York, have invented certain new and useful Improvements in Train-Control Communicating Elements, of which the following is a specification.

- 10 This invention relates to inductive influence communicating apparatus for automatic train control systems, and more particularly to the core structure of influence communicating devices.
- 15 In applying automatic train control to railways it is found necessary to transmit control influences from the trackway to the moving train, and on account of the difficulty experienced in transmitting such control influences by physical contact between the car-carried and trackway devices, such influences are preferably transmitted through an intervening air gap.

Various expediencies may be employed 25 for transmitting control influences through an intervening air gap, of which the method of transmitting control influences inductively has been found very satisfactory, and in employing this method it is found desirable to employ a magnetic core or yoke for this purpose. More specifically, it is proposed to employ a yoke of high grade magnetic material having enlarged projecting pole pieces, and in accordance with the 30 present invention, it is proposed to construct such a core of laminated magnetic material in which the laminæ are arranged in a vertical plane having its ends spread or fanned out, so to speak, whereby the 35 pole pieces may be conveniently attached to the laminæ in a manner to reduce the reluctance generally and so as to make the reluctance from any point of a pole piece to the main body of the core structure substantially the same.

Other objects, purposes, and characteristic features of the invention will, in part be pointed out and in part be apparent from the following description.

40 In describing the invention in detail reference will be made to the accompanying drawings, in which Fig. 1 is a plan view of the influence communicating element when used as a track element and an in-

verted view of the same when used as a car-carried influence receiving element, having a portion thereof cut away for clearness; Fig. 2 is a side elevation of the device shown in Fig. 1;

Fig. 3 is an end view of the device shown in Fig. 2;

Fig. 4 is a sectional view taken on the line 4—4, Fig. 2, as viewed in the direction of the arrows.

In describing the invention, the core structure embodying the same will for convenience be assumed to be a track device with the pole pieces extending upward as shown in Fig. 2, it, of course, being understood that the device may equally as well be used as a car-carried receiving element, in which event the pole pieces would face downward.

Referring to the drawings, there has been shown a core 2 of magnetic material in which the back yoke, or main portion of the core is of general cruciform cross section as more clearly shown in Fig. 4. This cruciform cross section is preferable because it is possible to place a coil thereon which has its inside turns more nearly circular, and so that the corners of the core are not so apt to cut the insulation of such coil. The laminæ for building up this core 2 consist of sheets, some of which have their body portion wide, as shown by the large dimensions in the cruciform cross section in Fig. 4, whereas the others have the body portions much narrower, as shown by the side portion of this cruciform cross section, the ends of each sheet of the laminæ being much larger to form legs to which the pole pieces are fastened, and being offset to one side as shown by the dotted lines in Fig. 2.

These sets of laminæ are piled up to form the cruciform core shown and are then riveted together by rivets 1 to form the core 2 of the cross section shown. In the corners between the projecting ends and the cruciform core are provided quarter rounds 3 constructed of suitable insulating material, such as wood, so that the core with its quarter rounds is of a rectangular cross section having rounded corners.

Near the ends of the cruciform cross section are clamps or cleats 4 which are bolted together by carriage bolts 5 which serve to hold the laminæ together, and more par-

ticularly to hold the quarter rounds in position. These cleats are made of insulating material and serve as the end portion of a spool on which the coil C may be wound or placed. The projecting ends of the laminæ are divided into two parts after the cleats have been tightened down and are fanned or spread out, as shown in Fig. 1 to provide room for the wooden wedge 6 driven or 10 forced therein.

After this wedge 6 has been put into place the guard plates 7, fastened to the outside of the fanned laminæ by bolts 8 and 9 passing through the laminæ and the wedge 6, 15 are applied. This wedge 6 not only serves as spacing means for the projecting laminæ, but also serves as an anchor to which the pole pieces 10 may be secured, these pole pieces being fastened to the wedges 6 by 20 bolts 11. As shown in Figs. 2 and 3 these bolts 11 have their heads counter-sunk into the pole piece 10 and pass through the wedge 6 and a suitable clamping plate 12 preferably of non-magnetic material, this 25 clamping plate bearing on both sides of the fanned laminæ. This structure allows the pole pieces 10 to be firmly clamped in place without injury to the wooden wedges 6. These bolts 11, in practice, are replaced by 30 suitable bolts for mounting the element on a car so as to have the proper relation with the apparatus with which it is to inductively communicate, and if used as a track device the pole pieces are preferably supported in 35 a suitable casing from which the core and coil structure are hung.

In order to further reduce the reluctance of the magnetic path of the core structure, the pole pieces 10 are provided with slots 40 13, extending from one edge thereof toward the center of the pole pieces. The provision of these slots 13 prevents the induction of eddy currents in the pole pieces 10 when the flux through the magnetic circuit of the 45 inductor is changed due to the passage of a car carried element in close proximity thereto.

The novel core structure embodying the present invention is designed and arranged 50 to withstand rough mechanical usage, is constructed so as to include a stack of continuous laminæ as distinguished from built-up laminæ so as to have not only a minimum, but substantially the same reluctance between substantially any point of the pole 55 pieces 10 to the cruciform back yoke or main portion of the core. In this structure the wedges 6 provide a simple means whereby the pole pieces may be fastened to the laminated core in a manner to provide good magnetic contact between the edges of the laminæ and these pole pieces. In practice, the edges of the laminæ to which the pole pieces 10 are to be fastened are faced so 60 that a good magnetic contact may be made

when the bolts 11 are tightened down, the wedges 6 serving further to maintain the fanned portion of the laminæ in the desired position so as to divide the core into two parts. This latter feature, as heretofore 70 mentioned, reduced the reluctance of the whole core structure considerably without increasing the amount of magnetic material employed.

Having thus shown a single specific embodiment of the invention, it is desired to be understood that this has been done to illustrate the nature of the invention rather than its scope, and that various changes and modifications may be made to adapt 80 the invention to the particular type of systems to which it is to be applied without departing from the scope of the invention or the idea of means underlying the same.

What I desire to secure by Letters Patent 85 of the United States is:—

1. A core structure for influence communicating apparatus for automatic train control systems comprising, a stack of laminæ of magnetic material fastened together 90 along an intermediate portion and having its ends spread out into a plurality of branches, and pole pieces fastened to the branched portion of said laminæ.

2. A core structure for influence communicating apparatus for automatic train control systems comprising, a stack of laminæ of magnetic material fastened together along an intermediate portion and having 95 its ends spread out into a plurality of branches, and blocks fastened between the branched ends of said laminæ.

3. A core structure for influence communicating apparatus for automatic train control systems comprising, a stack of laminæ of magnetic material fastened together 105 along an intermediate portion and having its ends spread out into a plurality of branches, blocks fastened between the branched ends of said laminæ, and pole pieces fastened to said blocks.

4. An influence communicating element for automatic train control systems comprising, a core consisting of a stack of laminæ of magnetic material fastened together 115 along an intermediate portion and having its end spread out into a plurality of branches, pole pieces fastened to the branched portion of said laminæ and a coil on said core.

5. An influence communicating element for automatic train control systems comprising, a core consisting of a stack of laminæ of magnetic material fastened together 125 along an intermediate portion and having its ends spread out into a plurality of branches, blocks fastened between the branched ends of said laminæ, and a coil on said core.

6. An influence communicating element

- for automatic train control systems comprising, a core consisting of a stack of laminæ of magnetic material fastened together along an intermediate portion and having its ends spread out into a plurality of branches, blocks fastened between the branched ends of said laminæ, pole pieces fastened to said blocks, and a coil surrounding said core.
7. An influence communicating element for automatic train control systems comprising, a core consisting of a stack of laminæ of magnetic material, said laminæ being fastened together along an intermediate portion, clamps surrounding said core at points adjacent to its ends, and a coil on said core between said clamps.
8. An influence communicating element for automatic train control systems comprising, a core consisting of a stack of laminæ of magnetic material, said laminæ being fastened together along an intermediate portion, clamps of insulating material secured about said core at points spaced from its ends, the ends of said core being spread into a plurality of branches beyond said clamps, and a pole piece clamped to each of said branched ends.
9. An influence communicating element for automatic train control systems comprising, a core consisting of a stack of laminæ of magnetic material, said laminæ being fastened together along an intermediate portion, clamps of insulating material
- secured about said core at points spaced 35 from its ends, the ends of said core being spread into a plurality of branches beyond said clamps, blocks fastened to said core between its spread ends, a pole piece fastened to each block, and a coil on said core between said clamps.
10. An influence communicating element for automatic train control systems comprising, a core of magnetic material, and pole pieces having slots in the edges thereof secured to the extremities of said core. 45
11. An influence communicating element for automatic train control systems comprising, a core consisting of a stack of laminæ of magnetic material and pole pieces 50 secured to the extremities of said core, each of said pole pieces having a slot therein extending from the edge toward the center thereof.
12. An influence communicating element 55 for automatic train control systems comprising, a core consisting of a stack of laminæ of magnetic material, the end of said core being spread into two branches, a block located between said branches, a plate on 60 the outside of each of said branches, bolts passing through said plates, said branches and said block and acting to secure said members together, and a pole piece bolted to said block in engagement with said 65 branched ends.

In testimony whereof I affix my signature.
CHARLES S. BUSHNELL.
